VALVE MECHANISM FOR GAS ENGINES.

No. 499,865.

Patented June 20, 1893.

UNITED STATES PATENT OFFICE.

HENRY WARDEN, OF PHILADELPHIA, PENNSYLVANIA.

VALVE MECHANISM FOR GAS-ENGINES.

SPECIFICATION forming part of Letters Patent No. 499,865, dated June 20, 1893.

Application filed March 9, 1892. Serial No. 384,188. (No model.)

To all whom it may concern:

Be it known that I, HENRY WARDEN, of the city and county of Philadelphia, State of Pennsylvania, have invented a certain new and useful Improvement in Valve Mechanism for Gas-Engines and other Uses, of which the following is a true and exact description, reference being had to the accompanying drawings, which form a part of this specification.

10 My invention relates to the construction and operation of slide valves and their actuating devices and is especially intended and adapted for use with gas-engines although it can be used also with slide valves applied to 15 other engines or machines.

The object of my invention is to provide a slide valve with clamping mechanism which will come into operation at a certain point or points in the movement of the valve holding 20 it at those points tightly to its seat with sufficient pressure to resist whatever tendency there may be to lift therefrom and which, during the movements of the slide valve, will release this pressure permitting the valve to 25 slide upon its seat with very little resistance and thus at the same time economize the power required to move the valve and avoiding injurious wear to the valve and to the seat.

30 Reference being now had to the drawings which illustrate my invention,—Figure 1 is a side elevation partly in section showing one end of a gas engine cylinder with slide valve and clamping mechanism. Fig. 1^A is an elevation of the mechanism for operating the valve-rod. Fig. 2 is a similar view showing a modification of the clamping device; and Figs. 3 and 4 similar views illustrating the movement of the valve and the action of the 35 clamping device.

A indicates the gas engine cylinder; B the piston or plunger working in it; E the head of the cylinder the outer face of which serves as the valve seat for the slide valve F.

45 C is a passage in the cylinder-head through which gas and air are admitted the said passage having a port C' in the valve seat; and D is the exhaust passage having a port D' in the valve-seat. Between these two ports is 50 the port E' leading to the interior of the cylinder and having preferably the conical form shown; the conical projection B' on the pis-

ton is adapted to substantially fit in and fill this conically-shaped port the purpose being to expel as perfectly as possible all the products of combustion from the cylinder when the piston moves back to its extreme position. In the slide valve F ports F' and F² are formed and valve-actuating mechanism as link G, bell-crank G', connecting-rod G², and a cam 55 on shaft H, not shown in the drawings, are provided to give the proper movements to the valve.

In an engine of the character illustrated in the drawings it is important that the valve 65 should be firmly held to its seat in the position shown in Figs. 1 and 2, that being the position occupied by the valve when the charge in the cylinder is exploded and the necessary pressure being that which will hold the valve 70 to its seat against the pressure of the expanded gases in the cylinder transmitted through it to the port E'. I therefore provide an intermittently-acting clamping device which will at that point in the travel of the valve come into 75 operation holding the valve to its seat with the necessary force but which, after the explosion and preferably before the valve moves from the position it occupies during the explosion will release the pressure on the valve 80 permitting the valve-actuating mechanism to move it without undue and unnecessary resistance; that is, the valve is permitted to move from the position shown in Fig. 2 to that shown in Fig. 4, then to that shown in 85 Fig. 3, and then back to the position shown in Fig. 2 before the clamp comes again into operation.

Referring more particularly to Fig. 1, the clamping device there shown consists of a 90 plate L pivoted at one end to standards K on the head of the cylinder and connected at the other end by means of a rod P with an eccentric P' on shaft H; bolts M M secure a plate M' to the plate L and through a perforation 95 in the plate L between the bolts M a clamping head O extends in such way as to rest against the valve F, a coiled spring N being held between the clamping head O and the plate M'; during the motion of the valve the 100 clamping-head O rests lightly against it or remains entirely out of contact with it; at the proper time, to wit, just before the explosion and when the valve is in the position shown,

in Fig. 1, the eccentric draws the plate L toward the valve, the head O resting and pressing against it and the spring N being compressed, the extent of the compression 5 of the spring, which can be readily regulated, of course regulates the amount of pressure exerted upon the valve; after the explosion and during the working stroke the motion of the eccentric governing the clamp- 10 ing device pushes the plate L away from the valve gradually releasing the pressure upon it and at the end of the working stroke the valve-actuating mechanism moves the valve in position to exhaust the cylinder to 15 receive a new charge and to close the port E' before the clamp again comes into operation. The importance of having a spring as N to transmit the clamping pressure to the valve is of course obvious; without the use of 20 some such device the clamp would have to be adjusted with the utmost nicety and could probably not be kept in order under the exigencies of practical use.

I have shown a light spring I secured to 25 standards J on each side of the slide valve (one only being shown in the drawings) which always exerts a light pressure to hold the valve to its seat; this spring is entirely independent of the clamping device and does not 30 exert pressure enough to offer any considerable resistance to the movement of the valve; its function being merely to hold the valve to its seat so that the explosive mixture at one point and the products of combustion at another point will move through their determined paths and not escape between the valve and its seat. As shown the clamp head O transmits its pressure to the valve through 35 the spring I, said spring intervening between the back of the valve and the clamp; this 40 however is a purely immaterial detail of construction.

Referring now to the modification shown 45 in Figs. 2, 3 and 4, the clamping device here consists of a lever L' pivoted to standards K' and having secured to it a cylinder R which extends over the back of the valve and has a portion R' of its surface planed off flat; the lever L' is actuated through a rod by an eccentric in the same way as explained as to Fig. 1. On the back of the valve F a strong spring N' is secured by means of a bolt Q passing through a slot or perforation n; another bolt, Q', passing through a slot n' in 50 the opposite end of the spring serves to hold it in position though not to clamp it to the back of the valve. As shown a second light spring, I', is secured upon the back of the

spring N'. During the movements of the valve prior to the explosion of the charge the 60 cylinder R remains in the position indicated in Figs. 3 and 4 with its flat side R' running substantially parallel to the back of the valve and pressing lightly against the spring I' but not against the spring N'; prior to the explosion of the charge, the valve being in the position shown in Fig. 2, the lever L' and cylinder R are moved to the position shown in that figure, the cylinder in turning pressing the light spring I' down against the spring 70 N' and then pressing against both springs until the force exerted is sufficient to hold the valve to its seat during the explosion, after which the cylinder returns to the position shown in Figs. 3 and 4 permitting the valve 75 to move freely upon its seat. The cylinder R with its flattened side R' is essentially a cam and it will be obvious that any cam with proper conformation can be used in like manner. It is also obvious of course that the 80 position of the spring through which I consider it preferable that the clamp should act upon the valve, is entirely immaterial so long as a construction is adopted by which a yielding pressure is exerted between the clamp 85 and the valve.

Having now described my invention, what I claim as new, and desire to secure by Letters Patent, is—

1. The combination with a valve seat, of a 90 slide valve adapted to move thereon, clamping mechanism arranged to hold the valve on its seat, a spring arranged between the clamping mechanism and the valve, means for moving the valve, and independent means for 95 actuating the clamp to release the pressure on the valve while it is moving and clamp it tight at a definite point in its path.

2. The combination with a valve seat, a valve adapted to move thereon and means for 100 operating the valve, of a clamp, means for moving the clamp so that when moved it will hold the valve to its seat and a spring between the clamping mechanism and the valve.

3. The combination with a valve seat, a 105 valve adapted to move thereon and means for operating the valve, of a spring operating to hold the valve to its seat with a light pressure, a clamp operating when put in operation to bear against the spring and hold the valve 110 firmly to its seat and means for operating the clamp.

HENRY WARDEN.
